UNITED STATES PATENT OFFICE

LESTER E. SPRAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed October 9, 1929. Serial No. 398,311.

My invention relates to railway traffic controlling apparatus, and particularly to apparatus for controlling a switch and the signals which govern traffic movements over the switch by means carried on a railway vehicle.

I will describe one form of apparatus embodying my invention, and will then point out the novel features thereof in claims.

10 The accompanying drawings, Figs. 1 and 2, when placed end to end with Fig. 1 on the left, constitute a diagrammatic view showing one form of apparatus embodying my invention.

15 Referring to the drawings, the reference characters 1 and 1^a designate the track rails of a stretch Y of railway track over which traffic may move in either direction, and which is connected with a siding Z by means of a switch W. Rails 1 and 1^a of stretch Y are divided by means of insulated joints 2 into sections A—B, B—C, C—D, D—E and E—F. Each of these sections is supplied with current by a battery 3 connected across the rails adjacent one end of the section, and is provided with a track relay which is designated by the reference letter G with a distinguishing exponent and which is connected across the rails adjacent the opposite end of the section.

20 Signals designated by the reference characters S¹, S², S³ and S⁴, respectively, govern the movement of traffic over switch W, signals S¹ and S² directing eastbound traffic, that is, traffic moving toward the right, as shown in the drawings, and signals S³ and S⁴ directing westbound traffic. Signals S¹ and S³ govern traffic movements along stretch Y over switch W in its normal position, as shown in the drawings, whereas signals S² and S⁴ govern traffic movements along stretch Y to or from siding Z over switch W reversed. Each of the signals, as shown in the drawings, is of the semaphore type.

25 Switch W can be operated by any suitable means, such, for example, as an electric motor M having an armature 148 and a field winding 154 as shown in the drawings.

30 Operated in conjunction with switch W are

contacts 137, 112, 51, 135, 56, 152^a, 152^b and 141. Of these, contacts 51 and 56 are closed when switch W is in its normal position only; contacts 137, 135 and 141 are closed when switch W is in its reverse position only; contact 112 is closed when switch W is in either its normal or its reverse position only; contact 152^a is closed at all times except when switch W is reversed; and contact 152^b is closed at all times except when switch W is in its normal position.

35 Motor M is controlled by a polarized switch relay N, the direction of energization of which is controlled by a polarized stick relay P. Relay N is also controlled by contacts 95, 96, 98 and 99 which are operated by the arms of signals S¹, S², S⁴ and S³ respectively, and each of which is closed only when its signal arm is in the stop position.

40 The energization of relay P in the normal direction by its pick-up circuits is controlled by back contacts of a neutral stick relay T, and the energization of relay P in the reverse direction is controlled by front contacts of relay T.

45 One pick-up circuit for relay T is controlled by track relay G⁵ and by an auxiliary stick relay K. The energization of relay K is controlled by track relay G⁵ and by an inductor device L which is located in the trackway adjacent the end F of section E—F. Inductor device L is in turn controlled by a vehicle carried inductor device J.

50 Inductor device L comprises two windings, 72 and 74, on a U-shaped core 73 of a magnetic material. Winding 72 is connected in series with the winding of relay K. Inductor device J comprises a winding 160 on a U-shaped core 161 of a magnetic material. The ends of winding 160 are connected together through a manually operable push button contact U.

55 An approach relay R is controlled by front contacts of relays G⁴ and G⁵. A second approach relay R¹ is similarly controlled by front contacts of relays G¹ and G².

60 A directional stick relay r is provided with a pick-up circuit which is controlled by front contacts of relays G⁵ and R. A

- stick circuit for relay r is controlled by back contacts of relays G^3 and G^4 , and a second stick circuit for relay r is controlled by contact 112 of switch W and by a back contact of relay R .
 5 A second directional stick relay r^1 is similarly provided with a pick-up circuit which is controlled by front contacts of relays G^1 and R^1 . A stick circuit for relay r^1 is controlled by back contacts of relays G^2 and G^3 , and a second stick circuit for relay r^1 is controlled by a back contact of relay R^1 .
 10 Relay T is provided with a second pick-up circuit which is controlled by a manually operable push button contact U^1 located adjacent signal S^2 .
 15 The arms of signals S^1 , S^2 , S^3 and S^4 have two positions indicating proceed and stop, respectively. Signals S^1 , S^2 , S^3 and S^4 are 20 selectively controlled by polar contacts of relay P when switch W is in a position which agrees with the direction of energization of relay P .
 25 By means of a control lever V , switch W can, in emergency, be disconnected from motor M and connected to a manually operable lever not shown in the drawings. Lever V has two positions, n and t . When lever V is in its n position, switch W is connected to 30 motor M , and when lever V is in its t position, switch W is connected to the manually operable lever. Lever V is equipped with four contacts, two of which, 101 and 44, are closed when lever V is in its n position only, 35 and the other two of which, 143 and 139, are closed when lever V is in its t position only. When lever V is moved to its t position, the circuit for relay N is opened at contact 101 of lever V , and the control circuits for signals S^1 , S^2 , S^3 and S^4 , through contacts of 40 relay P , are opened at contact 44 of lever V . By means of contacts 143 and 139, signals S^2 and S^4 may be cleared when switch W is in its reverse position while lever V is in its 45 t position. Contact 44 prevents the clearing of either signal S^1 or S^3 when switch W is in its normal position while lever V is in its t position.
 50 As shown in the drawings, energy is supplied to the various parts of the apparatus by batteries designated by the reference character Q with distinguishing exponents.
 55 Having thus described, in general, the arrangement and location of the various parts comprising my invention, I will now trace the operation of the apparatus.
 60 As shown in the drawings, all parts are in their normal condition, that is, all track sections between A and F are unoccupied, switch W is in its normal position, and signals S^1 and S^3 are indicating proceed. With the track sections unoccupied, all relays G are energized.
 65 With relays G^4 and G^5 energized, relay R is energized by its circuit passing from bat- 70 tery Q^1 , through wire 24, contact 25 of relay G^5 , wires 26 and 27, contact 28 of relay G^4 , wire 29, winding of relay R , and wires 30, 30^b and 30^c back to battery Q^1 . With relay R energized, relay r is energized by the circuit just traced for relay R as far as wire 26, thence through contact 31 of relay R , wire 32, winding of relay r , and wire 30^a to wire 30^b.
 75 With relays G^1 and G^2 energized, relay R^1 is energized by its circuit passing from battery Q^5 , through wire 33, contact 34 of relay G^1 , wire 35, contact 36 of relay G^2 , wire 37, winding of relay R^1 , and wires 30^b, 30^c and 30^f back to battery Q^5 . With relay R^1 energized, relay r^1 is energized by the circuit just traced for relay R^1 as far as wire 35, thence through wire 38, contact 39 of relay R^1 , wire 40, winding of relay r^1 , and wire 30^a to wire 30^b.
 80 With relays r and r^1 energized, relay P is energized by a normal pick-up circuit passing from battery Q^2 , through wires 4, 4^a and 4^b, contact 5^a of relay r^1 , wire 6, contact 7^a of relay r , wires 8, 10 and 11, contact 12^b of relay T , wires 13 and 14, winding of relay P , wire 15, contact 16^b of relay T , wires 17 and 18, contact 20^a of relay r , wire 21, contact 22^a of relay r^1 , and wires 23 and 23^b back to battery Q^2 .
 85 With relay P energized in its normal direction, the arm of signal S^1 is held in its proceed position by its circuit passing from battery Q^2 , through wires 4 and 4^c, contact 41 of relay G^3 , wires 42 and 43, contact 44 of lever V , wire 45, contacts 46 and 47^a of relay P , wire 48, contact 49 of relay R , wire 50, contact 51 of switch W , wire 52, the mechanism of signal S^1 , and wire 23^a back to battery Q^2 . The arm of signal S^3 is held in its proceed position by a circuit including the circuit just traced for signal S^1 as far as wire 48, thence through wire 53, contact 54 of relay R^1 , wire 55, contact 56 of switch W , wire 57, the mechanism of signal S^3 , and wires 23^a and 23^b back to battery Q^2 .
 90 With relay G^5 energized, relay K is energized by its pick-up circuit passing from battery Q^1 , through wire 24, contact 71 of relay G^5 , winding of relay K , winding 72 of inductor L , and wire 30^d back to battery Q^1 . A stick circuit for relay K is also closed, including the pick-up circuit just traced for relay K except passing around contact 71 of relay G^5 , through wire 75, and contact 76^a of relay K .
 95 Winding 74 of device L is constantly energized by its circuit passing from battery Q^1 , through wires 24 and 24^a, winding 74, and wire 30^e back to battery Q^1 .
 100 Inductor device J is shown with the terminals of its winding 160 connected together through push button contact U .
 105 I will now assume that a westbound train, carrying an inductor device J , enters sec- 110
 115
 120
 125
 130

tion E—F, de-energizing relay G^5 which, by its contact 25, in turn de-energizes relays R and r . With relay r de-energized a branch path is closed around contact 7^a of relay r in the circuit previously traced for relay P , this branch path passing from wire 6, through contact 7^b of relay r , wire 86, and contact 9^a of relay G^4 to wire 10. A second branch path is also completed around contact 20^a of relay r in the circuit previously traced for relay P this branch path passing from wire 18, through contact 19^a of relay G^4 , and contact 20^b of relay r to wire 21. The circuit for signal S^1 is opened at contact 49 of relay R , and hence the arm of signal S^1 moves to its stop position.

I will assume further that while the train is carrying device J over device L contact U , carried on the train is left closed. With contact U closed while device J is passing over device L winding 160 opposes the passage of magnetic flux through core 161 of device J from core 73 of device L . The increase of magnetic flux passing through core 73 due to proximity of the core 161 is therefore not great enough to induce an electromotive force in winding 74 of such a magnitude, in opposition to battery Q^1 as to cause relay K to open its front contacts.

As the train proceeds further and enters section D—E de-energizing relay G^4 the second pick-up circuit previously traced for relay P is opened at contacts 9^a and 19^a and a normal stick circuit is completed for relay P passing from battery Q^2 through wires 4, 4^a and 4^b, contact 5^a of relay r^1 , wire 6, contact 7^b of relay r , wire 86, contact 9^b of relay G^4 , wire 87, contact 88^a of relay G^3 , wire 90, contact 159^a of relay P , wire 14, winding of relay P , contact 158^a of relay P , wire 157, contact 156^a of relay G^3 , wire 155, contact 19^b of relay G^4 contact 20^b of relay r , wire 21, contact 22^a of relay r^1 , and wires 23 and 23^b back to battery Q^2 .

The train upon entering section C—D de-energizes relay G^3 which then opens, at its contacts 88^a and 156^a the stick circuit just traced for relay P . A pick-up circuit for relay P is then closed following the stick circuit just traced for relay P except passing from wire 87 thence through contact 88^b of relay G^3 , wire 11, contact 12^b of relay T , wires 13 and 14 winding of relay P , wire 15, contact 16^b of relay T , wire 17 and contact 156^b of relay G^3 to wire 155. Relay G^3 upon becoming de-energized opens, at its contact 41, the circuit for signal S^3 , the arm of which thereupon moves to its stop position.

When the train leaves section D—E, permitting relay G^4 to again become energized, relays R and r are again energized by their circuits previously traced. With relay r energized, the pick-up circuit last traced for relay P is opened at contacts 7^b and 20^b of

relay r and the pick-up circuit first traced for relay P is again closed.

As the train enters section B—C de-energizing relay G^2 , a stick circuit for relay r^1 is completed passing from battery Q^4 , through wires 58 and 58^a contact 105 of relay G^2 contact 106 of relay G^2 , wires 107 and 110, contact 111 of relay r^1 , winding of relay r^1 , and wires 30^a, 30^b and 30^c back to battery Q^4 . Relay G^2 upon becoming de-energized opens, at its contact 36, the circuit previously traced for relay R^1 , which then becomes de-energized completing a second stick circuit for relay r^1 passing from battery Q^4 , through wires 58, 58^a, 58^c 58^b and 58^c, contact 108 of relay R^1 , wires 109 and 110, contact 111 of relay r^1 , winding of relay r^1 , and wires 30^a, 30^b and 30^c back to battery Q^4 .

When the train leaves section C—D, relay r^1 continues energized by its second stick circuit, and relay P continues energized by its pick-up circuit first traced. Also when the train leaves section C—D, the arm of signal S^1 is operated to its proceed position by its circuit previously traced.

When the train leaves section A—B, relay R^1 again becomes energized by its circuit previously traced, and the arm of signal S^3 is operated to its proceed position by its circuit previously traced.

I will now assume that with all parts again in their normal condition, a west-bound train enters section E—F, and that while a device J , which is carried on this train, is moving over device L , the push button contact U , carried on the train, is held open. The magnetic flux passing through core 73 is thereby suddenly increased due to lowered reluctance of its magnetic circuit on account of the proximity of the core 161. This sudden increase of flux passing through core 73 induces an electromotive force in winding 72, which is opposite in direction to that applied to the circuit by battery Q^1 and is of sufficient magnitude to so counteract the electromotive force of battery Q^1 as to cause relay K to open its front contact 76^a. Relay K then continues de-energized while the train is passing through section E—F.

On account of the de-energization of relay G^5 by the train entering section E—F, relays R and r are again de-energized as already described. Relay R upon becoming de-energized opens, at its contact 49, the circuit for signal S^1 , the arm of which then moves to its stop position.

Upon the de-energization of relay K , relay T becomes energized by its pick-up circuit passing from battery Q^1 , through wires 24 and 75, contact 76^b of relay K , contact 77 of relay G^5 , wire 78, contact 79 of relay G^4 , wire 80, winding of relay T , and wires 30^a, 30^b and 30^c back to battery Q^1 . Relay T upon closing its contact 83 completes its stick circuit passing from battery Q^4 , through

wires 58, 58^a and 58^c, contact 81 of relay G³, wire 82, contact 83 of relay T, wire 84, winding of relay T, and wire 30^h back to battery Q² via Q⁴. Relay T upon becoming energized ⁵ reverses the polarity of the current flowing through the winding of relay P by the second pick-up circuit described for relay P. Relay P thereupon operates its polar contacts to the reverse position, opening ¹⁰ at its contact 47^a the circuit for signal S³, the arm of which then moves to its stop position. With the reverse polar contacts of relay P closed, and with all signals indicating stop, relay N becomes energized in the reverse direction ¹⁵ by its circuit passing from battery Q³, through wire 23^c, winding of relay N, wire 104, contact 103 of relay G³, wire 102, contact 101 of lever V, wire 100, contact 99 of signal S³, contact 98 of signal S⁴, wire 97, ²⁰ contact 96 of signal S², contact 95 of signal S¹, wire 94, contacts 93 and 92^b of relay P, and wires 91^a and 91 back to battery Q³. The reverse operating circuit for switch W is now closed passing from battery Q², ²⁵ through wires 4 and 4^a, contacts 145 and 150^b of relay N, wire 149, armature 148 of motor M, wire 147, contact 146^b of relay N, wire 123, contact 152^a of switch W, wire 153, field winding 154 of motor M, and wires 91^b and ³⁰ 91 to battery Q² via Q³. Switch W is thereupon operated to its reverse position. Contact 152^a is opened just before the completion of this movement of switch W, thereby opening the motor circuit. ³⁵ When switch W is reversed, a circuit is completed for signal S⁴ passing from battery Q², through wires 4 and 4^c, contact 41 of relay G³, wires 42 and 43, contact 44 of lever V, wire 45, contacts 46 and 47^b of ⁴⁰ relay P, wire 134, contact 141 of switch W, wires 142 and 144, mechanism of signal S⁴, and wires 23^a and 23^b back to battery Q². The arm of signal S⁴ then moves to its proceed position, opening its contact 98 and ⁴⁵ thereby de-energizing relay N. Relay T continues energized by its stick circuit, previously traced, and hence relay P continues energized in the reverse direction by its circuit already described, while the train is in ⁵⁰ section E—F.

When the train enters section D—E, a reverse stick circuit is completed for relay P passing from battery Q², through wires 4, 4^a and 4^b, contact 5^a of relay r¹, wire 6, contact 7^b of relay r, wire 86, contact 9^b of relay G⁴, wire 87, contact 88^a of relay G³, wire 90, contact 159^b of relay P, winding of relay P, wire 14, contact 158^b of relay P, wire 157, contact 156^a of relay G³, wire 155, ⁵⁵ contact 19^b of relay G⁴, contact 20^b of relay r, wire 21, contact 22^a of relay r¹, and wires 23 and 23^b back to battery Q².

When the train enters section C—D de-energizing relay T by opening the stick circuit for relay T, a normal pick-up circuit ⁶⁰

is again completed for relay P, through contacts 88^b and 156^b of relay G³ as previously traced. At the same time, relay G³ opens, at its contact 103, the circuit for relay N which is thereupon de-energized. With ⁷⁰ relay N de-energized because of the opening of contact 103 of relay G³, the normal energization of relay P does not cause relay N to be energized in its normal direction, and hence switch W continues in its reverse ⁷⁵ position until the train moves out of section C—D. On account of relay P being energized in its normal direction, signal S⁴ does not clear when the train leaves section C—D, and hence relay N now becomes energized ⁸⁰ in its normal direction by its circuit passing from battery Q², through wire 4, contacts 92^a and 93 of relay P, wire 94, contact 95 of signal S¹, contact 96 of signal S², wire 97, contact 98 of signal S⁴, contact 99 of signal ⁸⁵ S³, wire 100, contact 101 of lever V, wire 102, contact 103 of relay G³, wire 104, winding of relay N, and wire 23^c back to battery Q².

Relay N now being energized in its normal direction, motor M is operated by current flowing in the normal direction through its circuit passing from battery Q², through wires 4 and 4^a, contacts 145 and 146^a of relay N, wire 147, armature 148 of motor M, wire ⁹⁰ 149, contact 150^a of relay N, wire 151, contact 152^b of switch W, wire 153, field winding 154 of motor M, and wires 91^b and 91 to battery Q² via Q³. Upon the completion of the operation of switch W to its normal ⁹⁵ position, the arm of signal S¹ is again operated to its proceed position. Thereupon relay N becomes de-energized by the opening of contact 95 of signal S¹.

I will next assume that, with all parts ¹⁰⁰ again in their normal condition, a train on siding Z is to proceed into stretch Y over switch W. In order to reverse switch W for this traffic movement, a trainman closes contact U¹. If neither an eastbound nor a ¹⁰⁵ westbound train is approaching in stretch Y, relays r and r¹ are energized, and hence upon the closing of contact U¹, relay T is energized by a second pick-up circuit which passes from battery Q⁴, through wires 58 and 58^b, contact U¹, wire 127, contact 128 of relay r, wire 129, contact 131 of relay r¹, wires 132 and 80, winding of relay T, and wire 30^h back to battery Q⁴. Relays r and ¹¹⁰ r¹ would also be energized if an eastbound train were moving away from switch W, except under a condition which will hereinafter be explained or if a westbound train were moving away from switch W, and hence relay T would then also be energized ¹¹⁵ 120 by the closing of contact U¹. It follows therefore that a train approaching from either direction in stretch Y would prevent the control of switch W by push button U¹, but that a receding train would have ¹²⁵ 130

no effect on such control of switch W except under the condition just referred to.

- Upon the energization of relay T by contact U¹, relay P becomes energized in the reverse direction due to the reversal of polarity of the current supplied to the winding of relay P through its pick-up circuit first traced. The control circuits for signals S¹ and S³ are therefore opened at contact 47^a of relay P, and the arms of these signals then move to the stop position. Relay N then becomes energized in the reverse direction by the circuit already traced through contact 92^b of relay P, causing switch W to be operated to its reverse position. With switch W in its reverse position, signal S⁴ will be cleared by its circuit already traced, and signal S² will be cleared by its circuit which follows the circuit already traced for signal S⁴, as far as wire 134, thence through contact 135 of switch W, wire 136, mechanism of signal S², and wire 23^d back to battery Q².

When the train enters section C—D, relay G³, by opening its contact 41, breaks the circuits for signals S² and S⁴ which will then indicate stop. Relay T becomes deenergized by the breaking of its stick circuit at contact 81 of relay G³, and hence relay P is energized in the normal direction as first traced.

When the train enters section D—E, a stick circuit is closed for relay r passing from battery Q⁴, through wires 58, 58^a, 58^c and 58^e, contact 116 of relay G⁴, wire 117, contact 118 of relay G³, wires 119 and 120, contact 121 of relay r, winding of relay r, and wires 30^a, 30^b and 30^e back to battery Q⁴. Also when the train enters section D—E, relay R becomes de-energized due to the opening of its circuit by contact 28 of relay G⁴. With relay R de-energized a second stick circuit is completed for relay r passing from battery Q⁴, through wires 58, 58^a, 58^c and 58^d, contact 112 of switch W, wire 113, contact 114 of relay R, wires 115 and 120, contact 121 of relay r, winding of relay r, and wires 30^a, 30^b and 30^e back to battery Q⁴.

When the train leaves section C—D, relay G³ becomes energized and completes the normal control circuit for relay N. Relay N then closes its normal polar contacts completing the normal operating circuit for motor M which then moves switch W to its normal position. Switch W, while being operated to its normal position, opens at its contact 112 the second stick circuit for relay r, and the first stick circuit for relay r is also open at contact 118 of relay G³. Upon the completion of the movement of switch W to its normal position, the arm of signal S³ will be operated to the proceed position by its circuit already described.

On account of the control of the second

stick circuit for relay r by contact 112 of switch W, relay r becomes de-energized when a train is receding from switch W after having moved over switch W in its reverse position. On account of this arrangement, if a train, after moving out of siding Z, should stop east of signal S³ while preparing to reverse its direction of movement and to proceed westward over switch W normal, another train could not, upon entering the east end of section E—F, cause switch W to be reversed while the train adjacent signal S³ is starting to move westward.

I will now assume that with all parts again in their normal condition, a westbound train enters section E—F, and with its contact U open passes over inductor L causing relay T to be energized, and relay T then causing relay P to be energized in the reverse direction. I will also assume that at the time relay P becomes energized in the reverse direction, an eastbound train enters section A—B, de-energizing relay r¹. Relay P then continues energized in the reverse direction by a stick circuit passing from battery Q², through wires 4, 4^a and 4^b, contact 5^b of relay r¹, wires 85 and 87, contact 88^a of relay G⁴, wire 90, contact 159^b of relay P, winding of relay P, wire 14, contact 158^b of relay P, wire 157, contact 156^a of relay G³, wires 155 and 124, contact 22^b of relay r¹, and wires 23 and 23^b back to battery Q². With relay P energized in the reverse direction, relay N also becomes energized in the reverse direction although the eastbound train has entered section A—B. Switch W is then operated to its reverse position by motor M.

I will next assume that with all parts again in their normal condition an eastbound train enters section A—B, de-energizing relay r¹, I will also assume that a westbound train then enters section E—F, and with its contact U open, passes over inductor L causing relay T to become energized. The eastbound train, by de-energizing relay r¹, has already opened the pick-up circuit for relay P at contacts 5^a and 22^a of relay r¹, and has closed a normal stick circuit for relay P through contacts 5^b and 22^b of relay r¹. Hence the westbound train, if it does not energize relay T until after the eastbound train has de-energized relay r¹, cannot cause switch W to be operated to its reverse position.

I will now assume that on account of some emergency such, for example, as a failure of motor M, it is necessary to reverse switch W by hand for a train to move to or from siding Z. A trainman will therefore reverse control lever V to its t position thereby disconnecting switch W from motor M and connecting it to the manually operable lever. When lever V is reversed, the control cir-

cuits for signals S^1 and S^3 are opened at contact 44 of lever V, and hence the arms of signals S^1 and S^3 fall to their stop position. Upon the completion of the movement 5 of switch W to its reverse position by the manually operable lever, signals S^2 and S^4 will be operated to their proceed position, an operating circuit for signal S^2 now passing from battery Q^2 , through wires 4 and 4^c, contact 41 of relay G³, wire 42, contact 137 of switch W, wire 138, contact 139 of lever V, wires 140 and 136 mechanism of signal S^2 , and wire 23^a back to battery Q^2 . A similar operating circuit for signal S^4 10 follows the path just traced for the circuit for signal S^2 as far as wire 138, thence through contact 143 of lever V, wire 144, mechanism of signal S^4 , and wires 23^a and 23^b back to battery Q^2 . After the train has 15 passed switch W, a trainman will return switch W to its normal position by the manually operable lever, but the arms of signals S^1 and S^3 will not clear until lever V has been returned to its n position.

20 25 From the foregoing description and from the accompanying drawings, it is clear that my invention provides approach locking for a railway switch of the type which is controlled by apparatus carried on a moving vehicle. My invention also provides for clearing of signals governing over the switch when provision exists for operating the switch by hand and while the switch is in its reverse position, but prevents the clearing 30 of signals governing over the switch when the provision exists for operating the switch by hand and while the switch is in its normal position.

35 Other systems embodying subject matter 40 disclosed but not claimed herein are disclosed and claimed in a copending patent application of common ownership, Serial No. 658,540, filed August 21, 1923, by Bertram R. Padmore, for railway switch controlling apparatus, and in a copending patent application of common ownership, Serial No. 696,436, filed March 3, 1924, by Harry E. Brashares, for protected switch operating system.

45 50 Although I have herein shown and described only one form of railway traffic controlling apparatus embodying my invention, it is understood that various changes and modifications may be made therein within 55 the scope of the appended claims without departing from the spirit and scope of my invention.

Having thus described my invention, what I claim is:

60 1. In combination, a stretch of railway track containing a switch, trackway means for controlling the operation of said switch when a vehicle approaches said switch, means for preventing such operation of said 65 switch when a second vehicle moves toward

said switch but not when said second vehicle moves away from said switch, and means for controlling said trackway means from said first vehicle.

2. In combination, a stretch of railway 70 track containing a switch, trackway means for controlling the operation of said switch when a vehicle approaches said switch from a given direction, means for preventing such operation of said switch when another vehicle is moving toward said switch from a different direction, and means carried on said first vehicle for controlling said trackway means.

75 3. In combination, a section of railway 80 track containing a switch, trackway means for controlling the operation of said switch when a vehicle approaches said section from a given direction, means for preventing such operation of said switch when another vehicle is moving toward said section from a different direction, and means carried on said first vehicle for controlling said trackway means.

85 4. In combination, a stretch of railway 90 track including a section which contains a switch, trackway means for controlling the operation of said switch when a vehicle occupies said stretch in a given direction from said section, means for preventing such operation of said switch when a second vehicle occupies said stretch in a different direction from said section, and means carried on said first vehicle for controlling said trackway means.

95 5. In combination, a stretch of railway 100 track containing a switch, vehicle carried means for controlling the operation of said switch when the vehicle approaches said switch from a given direction, means for preventing such operation of said switch when a second vehicle is moving toward said switch from a different direction, and means for permitting such operation of said switch when said second vehicle is moving away 105 from said switch.

110 6. In combination, a stretch of railway track containing a switch, vehicle carried means for controlling the operation of said switch when the vehicle approaches said switch from a given direction, and means for preventing such operation of said switch when a second vehicle is moving toward said switch from a different direction.

115 7. In combination, a stretch of railway 120 track containing a switch, vehicle carried means for controlling the operation of said switch when the vehicle is in said stretch in a given direction from said switch, and means for preventing such operation of said switch when a second vehicle is in said stretch in a different direction from said switch.

125 8. A railway switch controlling system 130 comprising a power operated switch having

- a normal and a reverse position, a signal for governing traffic movements over said switch in its normal position, a second signal for governing traffic movements over said switch in its reverse position, means for controlling the operation of said switch, means for clearing said first signal when said switch is in its normal position, means for clearing said second signal when said switch is in its reverse position, means for at times providing for manual operation of said switch, means for preventing the clearing of said first signal when such provision exists for manual operation of said switch, and means for clearing said second signal when said switch is in its reverse position while such provision exists for manual operation of said switch.
9. In combination, a stretch of railway track containing a switch, a neutral stick relay, trackway means for controlling a pick-up circuit for said stick relay, a stick circuit for said stick relay controlled by traffic conditions within said stretch of track, a railway vehicle carried control means for controlling said trackway means, a polarized stick relay, a normal and a reverse pick-up circuit for said polarized stick relay controlled by said neutral stick relay, a normal and a reverse stick circuit for said polarized stick relay controlled by traffic conditions within said stretch of track, and means controlled by said polarized stick relay for controlling said switch.
10. In combination, a stretch of railway track containing a switch, a polarized stick relay, trackway means for controlling a normal and a reverse pick-up circuit for said stick relay, a normal and a reverse stick circuit for said stick relay controlled by traffic conditions within said stretch of track, vehicle carried means for controlling said trackway means, and means controlled by said stick relay for controlling said switch.
11. In combination, a stretch of railway track containing a switch, a neutral stick relay, a pick-up circuit for said stick relay controlled by manually operable means, a stick circuit for said stick relay controlled by traffic conditions within said stretch, a polarized stick relay, a normal and a reverse pick-up circuit for said polarized stick relay controlled by a back and a front contact respectively of said neutral stick relay, a normal and a reverse stick circuit for said polarized stick relay controlled by traffic conditions within said stretch, and means controlled by said polarized stick relay for controlling said switch.
12. In combination, a stretch of railway track comprising a first and a second section, a track switch for said first section, means for operating said switch, a stick relay, a pick-up circuit for said stick relay controlled by traffic conditions in said second
- section, a stick circuit for said stick relay controlled by a contact which is closed when and only when said switch is in one or the other of its extreme positions, and means controlled by said stick relay for controlling said switch.
- In testimony whereof I affix my signature.
LESTER E. SPRAY.
